VOLTAGE REGULATOR

Max Schwaiger, Nuremberg, Germany, assignor to
 Westinghouse Electric & Manufacturing Company,
 East Pittsburgh, Pa., a corporation of
 Pennsylvania

Application June 24, 1938, Serial No. 215,553
 In Germany August 27, 1937

3 Claims. (Cl. 171—119)

This invention relates to a method of and apparatus for regulating the voltage of alternating-current system circuits. The system includes control mechanisms that are actuated in accordance with variations of the system voltage from the desired value, and govern the operation of the voltage adjusting mechanism, such as regulating transformers, field rheostats of generators or synchronous condensers, and the like. The moving parts of the voltage adjusting mechanism may be operated by a pilot motor of the synchronous, asynchronous or commutator type, or by control magnets.

According to the invention, the current drawn from the circuit by the primary relay or regulator control member is automatically adjusted by at least one self-regulating inductance device having movable magnetizable parts, or winding parts, connected in the circuit of the primary relay in such manner that the primary relay is supplied with the necessary operating current only when the voltage to be regulated varies from the desired value in either direction by a predetermined amount. The self-regulating inductance device that is connected in the circuit of the primary relay is itself adjustable with respect to its electric and magnetic characteristics.

My invention will be better understood from the following description of certain preferred embodiments thereof, reference being had to the accompanying drawings illustrating the same, and in which:

Figure 1 illustrates an embodiment of a self-regulating inductance device such as used in the system of my invention;

Fig. 2 illustrates characteristic curves explaining the operation of the self-regulating inductance device;

Fig. 3 is a diagrammatic view of circuits and apparatus organized in accordance with one embodiment of the invention;

Fig. 4 is a diagrammatic view of the primary relay circuits of another embodiment of the invention; and

Fig. 5 illustrates curves showing the characteristics of the control element illustrated in Fig. 4 as applied to a three-phase alternating-current circuit.

Referring to Fig. 3, an alternating-current circuit is illustrated having conductors 1 and 2 leading from a source of supply at the right of the figure to supply current at a regulated voltage to a load to the left of the figure. In this circuit is connected an induction regulator or regulating transformer having series and shunt windings 3 and 4, respectively, that are relatively movable, as controlled by the operation of a pilot motor 5 which is controlled by the primary relay or voltage controlling element 6. The

relay 6 is provided with a shaft 7 that actuates a movable contact member 8 into engagement with the one or the other of two fixed contact members 9 and 12 to complete motor operating circuits from the secondary winding 13 of a transformer, the primary winding 14 of which is shown connected between conductors 1 and 2. The movement of the contact member 8 into engagement with the contact member 9 completes a motor operating circuit through conductors 15, 16 and 17 to operate the pilot motor 5 in one direction, and engagement of the contact member 8 with the contact member 12 completes a motor operating circuit through conductors 15, 18 and 17 to operate the motor 5 in the opposite direction. The operation of the motor 5 in one direction changes the relative position of the windings 3 and 4 of the induction regulator in such manner to increase the voltage supplied to the load, while operation of the motor 5 in the opposite direction varies the relative position of the windings 3 and 4 in such manner as to decrease the voltage supplied to the load in a well known manner.

For operating the shaft 7 of the primary relay device, two motor elements 21 and 22 are provided connected in opposition so that the motor 21 tends to rotate the shaft 7 in one direction, and the motor 22 tends to rotate the shaft 7 in the opposite direction. The motor 21 is provided with an armature 23 on the shaft 7 and windings 24 connected between conductors 1 and 2 through a network S₁, the purpose of which will be later described. The motor 22 is provided with a similar armature 25 on the shaft 7 and windings 26 connected between conductors 1 and 2 through a network S₂, similar to the network S₁.

Each of the networks S₁ and S₂ consists of a variable inductance and a fixed capacitance connected in parallel circuit relation to each other and in series with a fixed inductance, the network being connected in the energizing circuit of the motor elements 21 and 22, respectively. The variable inductances L₁ and L₂ may correspond to the self-regulating inductance device shown in Fig. 1 and explained by the curves in Fig. 2.

Referring to Fig. 1, an iron core 31 is provided having an air gap 32 in which a rotatable armature 34 of magnetic material is provided mounted on the shaft 33. In order to reduce the stray or leakage flux as much as possible, the energizing windings 35 provided on the core member 31 on opposite sides of the air gap 32 are cone-shaped, their adjacent ends approaching each other and partially surrounding the armature member 34. The space 36 between the inner edges of the windings 35 is made small to provide space sufficient only for the shaft 33 so as

to more easily attain the desired characteristic curves of the self-regulating inductance device. The desired magnetic and electrical values of the self-regulating inductance device are determined by the special shape of the magnetic poles 37 and of the rotatable armature 34. The rotatable armature 34 may be provided with a short-circuited damper winding 39, which creates a counter flux to oppose the magnetic flux penetrating the armature from the core member 31. This flux is of a variable nature, depending upon the position of the armature 34, so that the inductance of the self-regulating device is variable and is a minimum when the armature 34 is in its illustrated position.

As the energization of the winding 35 is varied in such manner as to rotate the armature 34 in the direction shown by the arrow 40, the shaft 33 is moved against the bias of a spring 41 connected to a cam 42 carried on the shaft 33 through a strap 43. As the armature 34 moves in a counter-clockwise direction, the inductance of the self-regulating inductance device increases in value until it reaches its maximum value. The characteristic curve of the inductance of the device may be controlled within certain limits by the design of the spring 41 and the shape of the cam 42 in such manner as to provide a varying torque with varying position of the shaft 33. For example, the cam 42 may be stepped as shown at 44, thus increasing the torque arm through which the spring 41 operates. Also, the winding 35 may be provided with taps for varying the number of turns therein in the controlled circuit.

Fig. 2 illustrates characteristic curves of the self-regulating inductance device shown in Fig. 1. As illustrated, the abscissa is plotted to show current I and the ordinate to show voltage E . The self-regulating inductance device has the characteristic curve indicated by L_1 in Fig. 2. Upon an increase in voltage from the value 0 to the value H_1 , the current increases along a straight line curve to the point A_1 . At this point, the armature 34 will start to operate against the bias of the spring 41, and the characteristic line of the device bends or takes a different direction between the points A_1 and A_2 corresponding to a voltage increase from the value H_1 to the value H_2 , at which voltage value the inductance of the self-regulating inductance device reaches its maximum value. As the voltage is further increased, the current values increase along the line indicated above the point A_2 . The two horizontal lines H_1 and H_2 therefore indicate the operating range of the particular self-regulating inductance device being considered. If a condenser is connected in parallel with the self-regulating inductance device L_1 corresponding to the condenser C_1 of Fig. 3, and having the characteristic curve C_1 shown in Fig. 2, the characteristic curve of the two elements may be plotted as shown by the line $L_1 C_1$. It will be noted that the characteristic curve of the current through a circuit including these two elements increases from the value 0 to a value B_1 when the voltage increases to the value H_1 , and between the lines H_1 and H_2 drops back again to the value represented by B_2 during the operating range of the self-regulating inductance device, and continues from that point to increase along the upper end of the line $L_1 C_1$.

If, however, in addition to the two elements of variable inductance and fixed capacity connected in parallel, another inductance having

the characteristic line L_1' is connected in series with the two parallel connected elements, completing the network S_1 illustrated in Fig. 3, the characteristic of this whole network assumes the form indicated by the line $L_1 C_1 + L_1'$ in the diagram of Fig. 2. By properly designing the values of the condenser C_1 and the series inductance L_1' , a network may be provided having a sharp bend in its characteristic curve indicating a sharp current change along the line H_2 with very little change in voltage.

A second circuit S_2 may be formed also having a fixed series inductance L_2' and a parallel connected fixed capacity C_2 and variable inductance L_2 as described for the network S_1 . The values of capacitance and inductance in this circuit may, however, be so selected that the characteristic curves of the network correspond to that shown by the curve S_2 in Fig. 2. The curve of the circuit S_2 is constructed from the characteristic lines L_2 , $C_2 + L_2'$ in a manner similar to the curve S_1 . The characteristic curves are so plotted as to show that the network potential falls near the center of the dead range between the voltage lines H_3 and H_4 . This provides a small range of voltage variation from the desired value E_n in the center of this range for stabilizing the regulator, so that for trifling potential variations from this value the regulator will not be brought into operation.

Referring again to Fig. 3, in which the several parts of the networks S_1 and S_2 are indicated by the same identifying letters as the curves illustrated in Fig. 2 showing their characteristics, it will be noted from the curves in Fig. 2 that the motor 21 connected to the network S_1 is supplied with current for values of voltage less than the desired value of E_n , and that the motor 22 connected to the network S_2 is supplied with current only for values of voltage higher than the desired value of E_n . For the desired voltage E_n , the self-regulating inductance device L_1 will be operating on that part of its characteristic curve above the point A_2 showing that it has been moved from the position illustrated in Fig. 1 throughout its range of operation, that is, through the range between the points A_1 and A_2 , or to its position of maximum inductance. The armature of the self-regulating inductance device L_2 , on the other hand, is in a field of operation below the value D_1 indicating that it is at rest at a position of minimum inductance value or corresponding to the position shown in Fig. 1.

If the voltage between conductors 1 and 2 increases above the desired value of E_n , current will be supplied through the network S_2 to the motor 22, as indicated by the curve S_2 in Fig. 2, causing the relay 6 to be operated in one direction to move the contact 8 into engagement with the appropriate contact 9 or 12 to operate the motor 5 to decrease the voltage supplied to the load. If the voltage between the load conductors 1 and 2 drops below the value represented by E_n in Fig. 2, the current supplied through S_2 will be zero, and the voltage supplied through the network S_1 and the motor 21 will increase rapidly, as shown by curve S_1 , causing the shaft 7 to be rotated in the opposite direction to cause engagement between contact member 8 and the other of the two contact members 9 or 12 to operate the motor 5 in a direction to decrease the voltage supplied to the load conductors 1 and 2.

Fig. 4 illustrates another embodiment of the

invention in which a single motor 50 is employed for operating the contact making relay in place of the two motors 21 and 22 of the form of the invention illustrated in Fig. 3. The motor 50 is shown as a two-phase motor having one phase winding 51 connected to the circuit to be regulated through a network S corresponding in nature to the networks S₁ and S₂ of Fig. 3, and a second phase winding 52 connected to the circuit through means which displaces the phase of the current drawn by this winding with respect to the phase of the current in the winding 51 by some value, such, for example, as 90°. For this purpose, a condenser 53 is provided. The nature of operation of the motor 50 does not require that the two phase circuit currents be displaced by exactly 90°. Other phase displacements providing sufficient torque may be employed. This arrangement may also be used in three-phase networks in which the phase voltages varying by 60° are available. When the neutral point of a three-phase system is accessible, one of the phase windings 51 may be connected between two phase conductors, and the other phase winding 52 between the remaining phase conductor and the neutral point. In this way, the desired 90° displacement between the voltages in the two windings is obtainable.

The value of the series inductance L' in the circuit S of Fig. 5 and the value of the parallel connected condenser C and the regulating inductance device L are so dimensioned that the characteristic curve of the network corresponds to that shown in Fig. 5. The curve of the self-regulating inductance device varies slightly between the points A₁ and A₂ from that shown in Fig. 2, in that it includes a step in the center of its operating range that is attained by the design of the armature of the device. The curve L₀ follows from combining the two curves C and L, and the curve S is attained if the inductance L' is added in series with the two parallel elements of the network.

If it is desirable that the motor element of the primary relay employ only a single-phase motor with a single winding circuit, the two control networks S₁ and S₂ may be connected in series with the winding. The two control circuits must have characteristic curves that are similar to those of S₁ and S₂ in Fig. 2, and will operate to control the flow of current through the single motor winding varying its phase angle from leading to lagging and vice versa as the voltage of the circuit varies in the one to the other direction from its desired value, to cause operation of the relay in the appropriate direction to effect the desired correction in voltage.

It will be noted that a regulating system organized in accordance with this invention results in small losses to the primary relay or controlling mechanism, since this mechanism does not take current from the line continuously but only when the regulated quantity varies in the one or the other direction from its desired value. Since, also, upon a slight variation in the regulated voltage from its desired value in the one direction or the other, the current change is quite abrupt, it is not necessary that the motor elements of the contact making primary relay be large.

Since many modifications will occur to those skilled in the art within the spirit of my in-

vention, I do not wish to be limited otherwise than by the scope of the appended claims.

I claim as my invention:

1. In a regulating system for governing the voltage of alternating-current circuits, means for adjusting the voltage of said circuit, control means therefor energized to be operated in accordance with variations in the regulated quantity from its desired value comprising two motor elements coupled together in opposition and having their energizing circuits separately connected across the circuit to be regulated in series with separate networks comprising a variable inductance and a fixed capacitance connected in parallel circuit relation to each other and in series with a fixed inductance, the variable inductance comprising an automatically regulated variable inductance device operable for effecting a sudden variation in inductance for permitting the required operating current to flow to the control means only upon variation in the regulated quantity from its desired value and to prevent the flow of operating current when the regulated quantity is substantially at its desired value.
2. In a regulating system for governing the voltage of alternating-current circuits, means for adjusting the voltage of said circuit, control means therefor energized to be operated in accordance with variations in the regulated quantity from its desired value and comprising two motor elements coupled together in opposition and having their energizing circuits separately connected across the circuit to be regulated, and networks connected in each motor element circuit and each including an automatically regulated variable inductance device operable from a minimum to a maximum value over a predetermined voltage range, and a condenser connected in parallel circuit relation thereto, the two regulating inductance devices and associated condensers being so dimensioned electrically and adjusted that their operation causes the two motors to carry substantially no current when the regulated voltage is at its desired value and that one only of them only to carry current when the regulated voltage is above its desired value and the other only to carry current when the regulated voltage is below its desired value.
3. In a regulating system for governing the voltage of alternating-current circuits, means for adjusting the voltage of said circuit, control means therefor energized to be operated in accordance with variations in the regulated quantity from its desired value comprising two motor elements coupled together in opposition and having their energizing circuits separately connected across the circuit to be regulated, and automatically regulated variable inductance devices connected in each motor element circuit and operable over a predetermined voltage range for permitting the required operating current to flow to the control means upon variation in the regulated quantity from its desired value and to prevent the flow of operating current when the regulated quantity is substantially at its desired value, said two automatically regulated inductance devices being so dimensioned electrically that when the regulated voltage is at its desired value the inductance value of one inductance device is a minimum and the inductance value of the other device is a maximum.

MAX SCHWAIGER.
